UNITED STATES PATENT OFFICE.

STANLEY A. FROLKING, OF CLEVELAND, OHIO, ASSIGNOR TO BRILLIANT GLASS PRODUCTS, INC., OF BRILLIANT, OHIO, A CORPORATION OF OHIO.

DESIGN FOR A TOWEL RACK.

Application filed January 7, 1927. Serial No. 20,300. Term of patent 7 years.

To all whom it may concern:

Be it known that I, STANLEY A. FROLKING, a citizen of the United States, residing at Cleveland, in the county of Cuyahoga and State of Ohio, have invented a new, original, and ornamental Design for a Towel Rack, of which the following is a specification, reference being had to the accompanying drawing, forming a part thereof.

In the drawings, Fig. 1 is a front view; Fig. 2 is a plan view and Fig. 3 is an end view of a towel rack showing my new design.

I claim:

The ornamental design for a towel rack substantially as shown.

STANLEY A. FROLKING.
